UNITED STATES PATENT OFFICE.

FREDERICK STRAHM, OF LAWRENCE, KANSAS.

CAR-SEAL.

1,231,216.

Specification of Letters Patent. Patented June 26, 1917.

Application filed August 5, 1914. Serial No. 855,262.

To all whom it may concern:

Be it known that I, FREDERICK STRAHM, a citizen of the United States, residing at Lawrence, in the county of Douglas, State 5 of Kansas, have invented certain new and useful Improvements in Car-Seals; and I do hereby declare the following to be a full, clear, and exact description of the invention, such as will enable others skilled in the art 10 to which it appertains to make and use the same.

This invention relates to improvements in car seals.

The principal object of the invention is to 15 provide a simple device of this character which can be locked without the use of any press.

Another object is to provide a device of 20 this character which can be quickly and easily broken when it is desired to open the car without the necessity for special tools for unlocking the seal.

Other objects and advantages will be apparent from the following description, when 25 taken in connection with the accompanying drawings.

In the drawings:

Figure 1 is a side elevation of the complete seal in locked position.
30 Fig. 2 is a vertical longitudinal sectional view therethrough.

Fig. 3 is a plan view.

Fig. 4 is a perspective view of the strap or ribbon of the seal.
35 Referring now more particularly to the accompanying drawings, 10 represents a substantially flat housing closed at one end and open at the other, the material at 10' in opposite faces of the housing being depressed 40 as shown to provide opposed inward projections the purpose of which will appear.

A ribbon or strap 11 of suitable metal has one of its ends formed with a struck up lug or tongue 12 inclining laterally and forwardly from one face thereof.

The extremity of this portion of the ribbon is folded over into four thicknesses as indicated at 11' and is inserted into the housing 10, where it is frictionally held between the projections above described against removal from the housing. The ribbon is further formed inwardly of the folded por-

tions 11' with a plurality of folds 11'' providing three thicknesses of material for a purpose that will subsequently be apparent. 55 The other end of the ribbon is formed with an opening 14 which is adapted to receive the tongue 12 when inserted in the housing, as clearly shown in Fig. 2. Thus when it is desired to employ the seal, the free end of 60 the ribbon is passed through the staple commonly provided on freight car doors and is then inserted into the open end of the housing 10 between a side wall thereof and the folded portion 11'' of the ribbon, the 65 tongue 12 passing through the opening 14 and thereby securing said free end against withdrawal. On each edge of the ribbon at points outwardly of the open end of the housing are formed the notches 15, these 70 notches being adapted for weakening these portions of the ribbon so that the same can be readily broken when the seal is to be removed from the lock. The housing and the ends of the ribbon will thus be broken away 75 from the ribbon and obviates the danger of the ends of the ribbon breaking within the housing.

What is claimed is:

A car seal comprising a housing having 80 a closed and an open end, inward projections formed on opposed faces of the housing adjacent its closed end, a ribbon of metal intermediately looped and having one of its ends bent to provide a plurality of 85 thicknesses of material inserted within the housing and frictionally held between the projections against removal therefrom, a portion of said end within the housing having a tongue struck outwardly therefrom, 90 and said end inwardly of the tongue being further bent to provide a plurality of thicknesses of material partially closing the open end of the housing, and the other end of the ribbon being provided with an opening and 95 being insertible in the housing to lockingly engage the tongue within the opening.

In testimony whereof, I affix my signature, in the presence of two witnesses.

FREDERICK STRAHM.
